United States Patent

Des. 238,868
Patented Feb. 17, 1976

238,868

RESTAURANT BUILDING STRUCTURE

Albert C. Friedrich, San Jose, Calif., assignor to
Wine Barrel Corporation, Campbell, Calif.

Filed July 30, 1973, Ser. No. 384,015

Term of patent 14 years

Int. Cl. D25—03

U.S. Cl. D13—1 B

FIG. 1

FIG. 2

FIG. 3

FIG. 4

FIG. 1 of the drawing is a view in side elevation of a building structure showing my new design;

FIG. 2 is a plan view of the building structure;

FIG. 3 is a front view of the building structure; and FIG. 4 is a rear view.

The other side of the structure not shown is essentially the same as the side shown in FIG. 1.

I claim:

The ornamental design for a restaurant building structure, as shown and described.
